UNITED STATES PATENT OFFICE.

JOHN WOLFINGER, OF NEW YORK, N. Y.

NON-REFILLABLE BOTTLE.

1,027,787.

Specification of Letters Patent.

Patented May 28, 1912.

Application filed February 10, 1912. Serial No. 676,843.

To all whom it may concern:

Be it known that I, JOHN WOLFINGER, a citizen of Austria, and residing in New York, in the borough of Manhattan, county 5 and State of New York, have invented certain new and useful Improvements in Non-Refillable Bottles, of which the following is a specification.

This invention relates to certain improvements in non-refillable bottles of that type which is provided in the neck of the bottle with a ball-valve which closes the bottle when the same is placed in upright position and which permits the pouring out of 10 the contents when the bottle is tilted, said non-refillable bottle comprising a bottle-neck provided with a bulge or enlargement, a dome-shaped portion within said bulging bottle-neck closed at the upper end and 15 forming an annular channel with the bottle-neck, and having inwardly projecting lips in the side-walls of said dome, an interior valve-seat at the lower end of the same, and a ball-valve seated therein and adapted to 20 establish or interrupt communication with the body of the bottle when pouring the contents or placing the bottle in vertical position.

In the accompanying drawing,—Figure 30 1 represents a vertical, central section through my improved non-refillable bottle, and Fig. 2 is a horizontal section, on line 2—2, Fig. 1.

Similar letters of reference indicate corresponding parts throughout the several figures of the drawings.

Referring to the drawing, the concave bottom *b* of the bottle is provided with a central opening which is closed by a plug 40 *b*¹ of cork, glass or other material, which is tightly closed or sealed after the bottle is filled. The bottle-neck *d* is provided with a bulge or enlargement *d*¹ within which is arranged a dome-shaped portion *e* which is 45 made integral with the bottle-neck at its lower end and is provided with a throat or restriction *e*¹, the tapering side-walls of the dome being concentric with the outer bulge of the bottle-neck and forming at the lower 50 end of the dome a seat for a ball-valve *f* which is permitted to move freely in the dome, but prevented from escaping from the same. The dome is provided in its upper side-wall with openings *o* and inwardly-bent lips *e*² which are formed of the stock of the dome before connecting the

same with the upper end of the body *a* and before melting the bottle-neck thereto, said lips *e*² being placed at an inward inclination to the side-wall of the dome so as to permit the egress of the liquid from the bottle when tilting the same over. The inwardly-bent lips *e*² form a cage for the ball-valve *f* by which the passage of the ball-valve beyond the lips is prevented and the return of the 60 valve to its seat facilitated. This construction of the lips is indicated in Fig. 2. While the lips permit the pouring of the liquid from the bottle on the opening of the ball-valve, they prevent the return of the liquid 65 to the interior of the dome on the return of the valve to its seat, the liquid passing around and being retained in the annular space between the wall of the bulging bottle-neck and the side-wall of the interior dome. 70 The lips furthermore prevent the insertion of any wire to the interior of the dome so as to tamper with the ball-valve and to hold the same so as to permit the exit of the liquid from the bottle. They also prevent 75 the valve from contact with the top of the dome, thereby eliminating danger of breaking the dome.

The ball-valve is preferably made of 80 glass, and is so arranged as to prevent the breaking of the inwardly projecting lips when pouring out the contents of the bottle.

The bottle-mouth can be closed in any known manner by means of a cork or otherwise, the refilling of the bottle being prevented partly by the rounded off upper edge of the dome and partly by the guard-lips, and mainly by the ball-valve which fits tightly on its seat as soon as exterior pressure is exerted thereon. The bottle can 90 only be refilled by being returned to the producers of the brand of liquors, medicine or other liquid in the bottle, when the bottom-plug is removed by melting or otherwise for 95 refilling the bottle.

I claim:

A non-refillable bottle comprising a body having a discharge mouth and a valve seat surrounding said mouth, a flaring dome integral with said body adjacent to said valve seat, said dome having an expanded closed top and being provided in its side wall near its top with discharge openings and with inwardly inclined guard lips on the lower side of said openings, a ball valve disposed 105 in said dome and adapted to close against said seat when the bottle is in normal position.

sition and to rest against said lips when the bottle is inverted; and a flaring neck surrounding said dome and provided with a contracted nozzle extending above the top 5 thereof, said neck being integrally united with said body on a circuit outside the connection therewith of said dome and forming an annular chamber between the neck and dome, the expanded top of the dome being

larger than the diameter of the discharge 10 nozzle.

In testimony, that I claim the foregoing as my invention, I have signed my name in presence of two subscribing witnesses.

JOHN WOLFINGER.
